CHARLES L. SHERMAN, OF PHILADELPHIA, PENNSYLVANIA

INSULATING-LINING.

1,086,338.

Specification of Letters Patent.

Patented Feb. 3, 1914.

Application filed June 30, 1913. Serial No. 776,498.

To all whom it may concern:

Be it known that I, CHARLES L. SHERMAN, a citizen of the United States, residing in the city and county of Philadelphia, State 5 of Pennsylvania, have invented a new and useful Insulating-Lining, of which the following is a specification.

My invention relates to a novel construction of an insulating sleeve or lining of the 10 character employed in incandescent lamp sockets to separate the metallic outer shell from the current carrying parts of the socket.

It has heretofore been proposed in this 15 art to line the metallic shell which surrounds other metallic parts serving to carry or regulate an electric current with an insulating sleeve or lining stamped, formed or pressed out from sheets of fiber or similar 20 material shaped so as to form an approximately cylindrical lining of the proper shape, said insulating lining being made of a single piece of suitable material such as fiber, hard rubber or the like of varying 25 diameter, said lining being made by taking tubes of insulating material, cutting them into suitable lengths and submitting them to the action of dies. These insulating fibrous linings which have been heretofore em- 30 ployed have been open to objection, since it has been sometimes found in practice to be impractical to make said linings invariably fit the shell with just the requisite closeness to prevent the linings falling out 35 and still allow of their ready insertion and removal. Furthermore, if such fibrous lining of the prior art under certain conditions fitted the shell with just the proper closeness, such requisite close fit would not be 40 maintained under the varying conditions arising from moisture and temperature or climatic conditions and with these linings there was therefore constant danger of the 45 lining dropping out of the shell, which has been a recognized defect in this class of linings, to remedy which attempts have heretofore been made without satisfactory results. To obviate these defects, it has been 50 heretofore proposed to provide an insulating sleeve or lining for such incandescent lamp sockets, composed of paper or similar elastic insulating material having a portion of its periphery of larger diameter than the 55 part of the shell within which it is to fit, so that as the lining is inserted in the shell, this elastic or resilient portion will be com-

pressed and by this elasticity will maintain the requisite frictional contact with the inner periphery of the shell. This latter class of elastic linings has been formed from 60 paper tubing, consisting of closely wound layers of paper formed by the action of suitable dies, which draw down the tube for a portion of its length, such a paper lining being elastic and of a diameter somewhat 65 larger than the diameter of the part of the shell in which it is to fit, an additional advantage of this last mentioned paper lining being that it can be produced at materially less expense than the fibrous lining heretofore employed, to which I have referred. I 70 have, however, found by practical use that even in these last mentioned paper linings, which are formed with a reduced end portion so proportioned, that said reduced end 75 is designed to spring outward somewhat, to give the requisite frictional contact with the inclosing shell, that owing to climatic and other conditions even these devices fail to 80 obviate the above defects and I have therefore devised the present invention, which 85 consists of an insulating sleeve or lining, comprising a tube of suitable elastic or resilient material, which is so proportioned with respect to the coacting metallic shell, 90 that all parts of the lining are out of contact with the interior surface of the shell with the exception of one or more frictional contact points which are pressed outwardly, 95 preferably from the larger periphery of the lining, so as to extend entirely around the outer periphery of said lining, the requisite frictional contact between the outer surface of the lining and the inner juxtaposed portion of the shell being attained by reason 100 of the enlarged annular beads or protuberances upon that portion of the lining preferably of largest diameter, and to this end my invention consists of a novel construction 105 of an insulating sleeve or lining comprising an elastic tube having end portions of different diameters and an annular bead or beads or their equivalent suitably formed upon preferably the larger portion of the lining, so as to extend entirely around the outer periphery of said lining, whereby the 110 requisite frictional contact between the lining and the surrounding shell is obtained, the portion of the lining of smallest diameter being spaced entirely away from the inner surface of the inclosing shell.

It further consists of other novel features

of construction, all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

15 Figure 1 represents a side elevation of one form of an insulating lining, embodying my invention. Fig. 2 represents a sectional view of another lining, embodying my invention, placed in position within the surrounding metallic shell of the incandescent lamp.

Similar numerals of reference indicate corresponding parts in the figures.

Referring to the drawings, in carrying out 25 my invention for the purposes of cheapness, I form the elastic insulating sleeve or lining from a paper tube, consisting of closely wound layers of paper closely compacted together, which after having been subjected to 30 the action of suitable dies assumes the shape seen in Figs. 1, 2 or 3.

In the embodiment seen in Fig. 1, the lining 1 has an end portion 2 of larger diameter and the portion 3 of smaller diameter, both 35 portions 2 and 3 being shaped, so that they are of slightly less diameter, than the metallic shell 8 into which they will be inserted, the portions 2 and 3 being joined by the shoulder 4. At a suitable step in the manu- 40 facture or formation of the lining by means of dies or otherwise, I provide in any suitable manner the frictional retaining device, which comprises an annular bead or enlargement 6 integral with the larger portion 2 of 45 the lining and may be located in any desired proximity to the shoulder 4 above which is the reduced portion 3, said bead extending entirely and continuously around the outer periphery of said lining.

50 In the construction seen in Fig. 2, I form preferably integral with the portion 2 of largest diameter, a plurality of annular enlargements, rings or beads 7, which are located below the shoulder 4 above which is 55 the reduced portion 3, said beads extending entirely and continuously around the outer periphery of the lining.

In all the embodiments of my invention it will be apparent that the insulating lining 60 proper is throughout the greater portion of its outer periphery spaced to a slight extent away from the metallic shell 8 inclosing it, and that the frictional contact necessary to retain the lining within the shell is created by

reason of the annular beads 6 or a plurality of 65 beads 7, or their equivalents, as will be evident to those skilled in this art, the lining thus formed having the requisite elasticity and compressibility and being especially adapted for use in incandescent lamp sockets 70 to meet all practical requirements and being so constructed that the lining for the outer shell will be at all times retained in the shell and under all conditions by the frictional contact devices without danger of dropping 75 out and without offering undue resistance to its removal.

I am aware that the patent to Painter #718,378, granted January 13, 1903, discloses the employment of a lining of fiber, 80 rubber or similar insulating material, which is adapted to contact for the greater portion of its outer periphery with the inclosing metallic shell, and that it is a common right to employ a lining of this character by reason of the decision in General Electric Company vs. Yost Electric Manufacturing Company, 139 Fed. Rep., p. 568, wherein a product of the general character referred to was held to be public property and also it is a 90 common right to employ a paper tube having its diameter reduced for a portion of its length, either alone or in combination with a metallic shell, in view of the decision in Marshall vs. Pettingell-Andrews Company, 95 164 Fed., 362, and I hereby make no claim *per se* to the use of a fiber, rubber or paper lining or to the mode of manufacturing the same, my present invention being differentiated from the above devices and relating 100 solely to an insulating lining of materially less diameter than the juxtaposed periphery of the metallic shell, which is to fit said lining, the latter being held in position within said shell solely by reason of the frictional 105 contact of an annular bead or beads or their equivalent, whereby the lining will be retained within the outer shell at all times and under all conditions without danger of dropping out and without offering undue resistance to its removal.

I desire to lay special emphasis upon the fact that the portion of the smaller diameter 3 is entirely out of contact with the inclosing shell 8, as is the portion 2 of greater 115 diameter, the shell being retained in position solely by the frictional contact of the bulged portions 6 or 7. In practice I prefer to employ the construction seen in Figs. 1 or 2, since a lining with the resilient projection extending diametrically around its larger diameter is more effective than one having longitudinal corrugations, since in the latter construction the convexed longitudinal portions contact with the shell longitudinally and since the lining is flexible, it is not held in place as satisfactorily as when the resilient convexed portions extend

around the larger diameter of the lining, as seen in Figs. 1 and 2, in which construction a greater area or contacting surface is afforded between the lining and shell, where-
5 by the lining is resiliently engaged with the shell in a more uniform and rigid manner, which frictional contact is maintained until the lining is entirely removed from the shell.

I have not deemed it necessary to describe
10 in detail the various steps employed in the formation of my novel insulating lining having the integral continuous bulges or annular beads thereon, as the same, *per se*, form no part of the present invention, and
15 I have also deemed it unnecessary to de-
script detail any specific means or mech-
anism for forming the continuous annular
frictional bead 6 or the plurality of annular
frictional beads 7, as I do not desire to be
20 limited to any particular means or steps
whereby the same may be produced. I have
also deemed it unnecessary to indicate the
slots and openings usually formed in the
linings or sockets, as these are of course
25 made to suit the socket in which the lining
is to be used.

It will now be apparent that I have de-
vised a novel and useful construction of an
insulating lining, which embodies the fea-
30 tures of advantage enumerated as desirable
in the statement of the invention and the
above description, and while I have, in the
present instance, shown and described a
preferred embodiment thereof which has
35 been found in practice to give satisfactory
and reliable results, it is to be understood
that the same is susceptible of modification
in various particulars without departing
from the spirit or scope of the invention or
40 sacrificing any of its advantages.

Having thus described my invention, what

I claim as new and desire to secure by Let-
ters Patent, is:—

1. In an incandescent lamp socket, an in-
sulating lining adapted to be inserted with-
45 in an outer shell, consisting of a tube of
elastic and compressible material having
thereon, an outwardly projecting bead ex-
tending around the outer periphery of said
lining. 50

2. An insulating lining consisting of a
tube having end portions of different diam-
eters and composed of elastic material, the
larger of said portions being provided with
a continuous outwardly projecting bead ex-
55 tending entirely around the outer periphery
of said lining.

3. The combination of a metallic shell,
with an insulating sleeve consisting of an
elastic compressible paper tube of less diam-
eter than said shell, the larger portion of
said tube being provided with a continuous
outwardly projecting bead extending en-
tirely around the outer periphery of said
tube and adapted to engage the juxtaposed 65
contiguous inner portion of the inclosing
shell.

4. In an incandescent lamp socket the
combination of a metallic shell, with an in-
sulating sleeve consisting of an elastic, com-
pressible paper tube of less diameter than
said shell, the larger portion of said tube
being provided with a plurality of continu-
ous outwardly projecting beads extending
entirely around the outer periphery of said
75 tube adapted to engage the juxtaposed con-
tiguous inner portion of the inclosing shell.
